UNITED STATES PATENT OFFICE.

HUGO JOHN WALTER, OF BRADFORD, PENNSYLVANIA, ASSIGNOR TO CONSOLIDATED MACHINE COMPANY, OF BRADFORD, PENNSYLVANIA.

APPARATUS FOR MANUFACTURING WINDOW-GLASS CYLINDERS.

1,318,190.

Specification of Letters Patent.

Patented Oct. 7, 1919.

Application filed January 31, 1919. Serial No. 274,242.

To all whom it may concern:

Be it known that I, HUGO JOHN WALTER, a citizen of the United States, and a resident of Bradford, in the county of McKean and 5 State of Pennsylvania, have invented certain new and useful Improvements in Apparatus for Manufacturing Window-Glass Cylinders; and I do hereby declare the following to be a full, clear, and exact description of the invention, such as will enable others skilled in the art to which it appertains to make and use the same.

My invention relates to an improvement in apparatus for manufacturing window 15 glass cylinders.

In one type of apparatus used in this art, a hoisting cage carries a blower having a downwardly projecting air outlet constructed to make an air tight but yielding 20 and flexible connection with the upper end of the blow pipe carrying the bait, the air being taken into the blower at the open side of the latter and forced out through the blow pipe and bait. The pressure of air 25 required to expand the cylinder and support it against collapsing is comparatively small being but a fraction of an ounce greater than the outside air, and this pressure is controlled by the speed of the fan or 30 blower which is under the control of the operator drawing the cylinder.

With such construction, if during the drawing of a cylinder, the motor stops, the air within the cylinder is free to escape 35 therefrom through the blower casing, and thus leave the plastic part of the cylinder without the inside support necessary to maintain its shape.

This invention relates to the type of apparatus above referred to and its object is to provide means whereby when the supply of air to the glass cylinder from the blower stops, back leak or vent from the cylinder through the blower will be absolutely prevented.

I would have it understood that the inventive idea involved is not however dependent on the particular construction of apparatus as shown, and that changes may 50 be made without departing from the spirit of my invention.

In the accompanying drawings; Figure 1 is a view in elevation partly in section of an

apparatus embodying my invention, and Figs. 2 and 3 are views of modifications.

55

1 represents the casing provided with the usual openings 2 at the side, one of which is permanently closed against all leakage of air by the plate 3, which is bored centrally for the passage of the shaft 4 carrying the fan or blower blades 5. The closure plate 3 constitutes a bearing for the shaft 4, which latter has a close fit therein to prevent air leakage, and is coupled up to a motor 14 which drives the same.

65

The opening 2 at the outer side of the casing 1 is adapted to be closed by the valve 6, which is constructed to prevent air leakage when it is closed. This valve is mounted on pins 7 or otherwise supported in position 70 over opening 2, and is pivotally connected at 8 with the lever 9 fulcrumed to the bracket 10 carried by the casing 1. The lower free end of this lever is connected by the spring 11 to the casing 1, which spring tends to 75 normally hold the valve in its closed position, and the upper end of the lever carries the core 12 of a solenoid, the coil 13 of the latter being carried by the casing 1. The coil 13 is connected in series, shunt or 80 parallel, with the motor 14 driving the blower, in such manner that when current is supplied to the motor the coil will be energized thus pulling inwardly on the core and moving the valve 6 away from its seat. The 85 valve and its seat may have ground joints to prevent leakage of air around the valve.

85

From the foregoing it will be seen that when the motor which actuates the blower, is started, the coil will be energized, thus 90 pulling inwardly on the core and opening the valve for the entrance of air. The instant the motor actuating the blower stops for any reason the coil 13 will be deenergized thereby releasing the core and permitting 95 the spring 11 to move the valve to its closed position and thus positively and completely close the only opening in the blower through which any air could pass outwardly from the cylinder.

100

The blower casing is provided with an air pipe 15 leading therefrom which has a coupling 16 for the attachment of the blow pipe 17 carrying the bait 18, and the whole including the motor for actuating the blower 105 is carried on a cage 19 suspended from a

suitable cable and constitutes the drawing mechanism of the cylinder forming apparatus.

In some systems the amount of air supplied to the glass cylinder is greater than the amount needed to distend and maintain the shape and size of the cylinder, and in such systems it is necessary to provide a vent through which the air in the cylinder can escape. Such systems are known as the open system. With my system, which is a closed system, no vents or leakage openings are provided, the aim being to supply only the requisite amount of air needed as the drawing of the cylinder progresses, and then preventing the escape of any in the event of a stoppage of the blower driving motor.

It is clearly evident that instead of using an outside valve as shown, the valve may seat against the inner face of the casing and close by back pressure as illustrated in Fig. 2, or a rotary valve having ports to register with ports in the casing and operated by a magnet or a solenoid could be employed as in Fig. 3 hence I do not confine myself to the details shown.

Having fully described my invention what I claim as new and desire to secure by Letters Patent, is:—

1. An apparatus for supplying air to a glass cylinder during the drawing operation, comprising a blower having an air inlet, a valve for closing said inlet and automatically operating devices for actuating the valve to close the air inlet when the blower stops.

2. An apparatus for supplying air to a glass cylinder during the drawing operation, comprising a blower having an air inlet, a valve for closing said inlet and automatically operating devices for actuating the

valve to close the air inlet when the blower stops and for holding it closed while the blower is not operating.

3. An apparatus for supplying air to a glass cylinder while being drawn comprising a blower having an air inlet, a valve for closing said inlet, and electro-magnetic device for opening the air valve.

4. An apparatus for supplying air to a glass cylinder during the drawing operation comprising a blower having an air inlet, a valve for closing said inlet, an electric motor for the blower and electro-magnetic means for opening the said air valve, the said device having connection with the motor whereby when the latter stops the device will release the valve and permit it to close.

5. An apparatus for supplying air to a glass cylinder while being drawn, comprising a blower having an air inlet, a valve for closing said inlet, a spring for normally holding the valve closed and electro-magnetic device for opening the valve and for holding it open while the blower is in operation.

6. An apparatus for supplying air to glass cylinders during the drawing operation, comprising a mechanical blower having an air inlet and an air outlet, the blower being located intermediate the inlet and outlet, the outlet having means for attaching a blow pipe and bait thereto, and an automatically operating valve for closing the inlet when the blower is not operating.

In testimony whereof, I have signed this specification in the presence of two subscribing witnesses.

HUGO JOHN WALTER.
